UNITED STATES PATENT OFFICE.

WILLIAM H. STINARD, OF SYRACUSE, NEW YORK.

DESIGN FOR A CONFECTION.

SPECIFICATION forming part of Design No. 14,010, dated June 26, 1883.

Application filed May 7, 1883. Term of patent 3½ years.

To all whom it may concern:

Be it known that I, WILLIAM H. STINARD, of Syracuse, in the county of Onondaga, in the State of New York, have invented new and 5 useful Improvements in Design for Confections, of which the following, taken in connection with the accompanying drawings, is a full, clear, and exact description.

This design consists in a confection composed of an annular base, a cylindrical mounting, and a glazing applied to the latter, the whole presenting a very delicate and tempting appearance.

In the annexed drawings, Figure 1 is a side 15 view of a confection embodying my design, and Fig. 2 is a vertical transverse section of the same.

a denotes the annular base; *b*, the cylindri-

cal mounting on said base; and *c* represents the glazing applied to the top of the mounting *b*.

What I claim is—

The design for confections, consisting of the annular base *a*, cylindrical mounting *b*, and top glazing, *c*, substantially as described and 25 shown.

In testimony whereof I have hereunto signed my name and affixed my seal, in the presence of two attesting witnesses, at Syracuse, in the county of Onondaga, in the State of New York, 30 this 3d day of May, 1883.

WILLIAM H. STINARD. [L. s.]

Witnesses:

FREDERICK H. GIBBS.
WILLIAM C. RAYMOND.
